CHARGE FORMING DEVICE

Chester F. Klaburner, Baltimore, Md.

Application September 19, 1942, Serial No. 458,939

3 Claims. (Cl. 123—121)

1

This invention refers to internal combustion engines and more particularly to the control of the fuel feed mechanism and systems therefor. It has among its objects to provide an arrangement and mechanism for improving the distribution of fuel to the engine proper; for providing a device for augmenting the functions and operations of the carburetor used; and for automatically feeding additional fuel to boost the carburetor supply. Another object is to have the device arranged for insertion in the conventional piping and connections about the engine, carburetor and control valves, so that it will not materially disturb their positions and operations, and of a size and proportion to fit readily in place. A still further object is to increase the efficiency of the fuel used in the engine to a substantial degree and eliminate various tendencies to use it wastefully through the use of a carburetor alone. Means for automatically operating the spark control in cooperation with the augmented fuel supply to the engine is also included in the objects of this invention.

Other objects will become apparent as the invention is more fully set forth.

This invention involves the use of extra chambers, mechanism and connections between the main supply tank and the engine of a conventional internal combustion engine. It is preferably used in parallel with the carburetor and its connections to augment the action of the latter and make the mixture of fuel gases to the engine more effective for explosive combustion. It consists in general of a booster device consisting of a float chamber attached to the piping running from the main fuel supply tank and feeding into the manifold of the engine. The chamber has a float for controlling the amount of liquid fuel therein and a valve for admitting predetermined quantities of air thereto. This chamber forms a mixing chamber for the air and liquid fuel fumes to combine in, in predetermined proportions. The air valve works automatically and keeps a sufficient amount of air in the tank to provide an explosive mixture with the gaseous fuel that evaporates and mixes in it. This is drawn into the engine with the mixture that is drawn through the carburetor. The total amount of fuel mixture drawn into the engine with the booster supply is about equal to that drawn in when the carburetor is used alone in the conventional system. The general action of the conventional carburetor delivers relatively raw gasoline to the engine in proportion to the vacuum action produced by the running engine.

2

The addition of the booster drive in parallel allows the fuel gas vapors to mix with air through the automatic valve in the relatively large chamber space provided for this action. This mixture is not as rich as that coming from the carburetor but is quite saturated. The introduction of air alone to the mixture going from the carburetor has been found to improve it but the dilution is apt to be too great and erratic to give proper combustion. The introduction of the air impregnated with fuel vapors mixed in the booster chamber works better and avoids the excessive dilution caused by the use of raw air alone. As the connection to the manifold is at a location approximately the same as where the carburetor is attached, the total fuel mixture to the engine is mixed together. This makes the mixture reaching the engine partially carburetor mixture and partially booster mixture, the two combining mechanically to make a mixture having a fuel content different from either alone, and making the intermixture of fuel and air more homogeneous. This homogeneous condition being due to the wet or over-saturated condition of the gasoline mixture from the carburetor turbulently combining with the relatively dry and non-saturated gasoline from the booster chamber and resulting in a nearly perfect explosive mixture as it enters the engine.

30 In the drawings which illustrate a form of this invention by way of example:

Figure 1 is a plan view of the arrangement of the apparatus used in this invention, and

Figure 2 is a side elevation of the device with parts broken away to show the internal construction of the apparatus.

Similar reference characters refer to similar parts throughout the drawings.

In order to provide a more comprehensive description of the invention, reference is made to 40 the shop manual 1937-1938 series of the Packard Motor Car Company, page 54, where the Stromberg Carburetor EE-14 is indicated and its adjustments described. This description may be readily found in other literature and is well understood among those familiar with automobile construction and maintenance. The reference is made specifically in this case for the convenience of the readers of this specification and to enable them to identify the specific details of 50 construction pertaining to the conventional equipment used in the system of this invention. This carburetor has been selected arbitrarily and could be substituted by other well-known types of carburetors of other makes. It is designated as

1, with an intake pipe connection 2 coming from a fuel tank 3 filled with gasoline 4, vent 5 and cap 6. Its outlet connection 7 is attached to the manifold 8 of an engine. It has a butterfly valve 9 pivoted diametrically and positioned to the manifold and air intake 23. A vacuum automatic spark control device 10 with a diaphragm 11, cables 12 and distributor timing shaft 13 (see Figure 137 in same manual) is attached to the vacuum piping 14 at the side 15 of the carburetor and controlled through the use of a vacuum hole 16 opening into the carburetor. A control valve or inspirator 17 is connected to the vacuum piping 18 by adjustment nut 22 as indicated and serves to provide a pulsating control to the flow of fuel to the manifold from the booster device. This valve 17 has a connection 28 and tubing 19 that connects with the metal float chamber booster device 20. This device has an automatic air valve 21 for admitting air into it in predetermined quantities to the upper portion 24 and the amount of air admitted is determined by the adjustment of regulator 25. It has also a ball float 26 inside with a rod 27 and seat 29 for opening and closing the valve 30, provided as shown. The air-valve 21 is preferably placed in the top portion of the float chamber 21 relatively far above the gasoline level, so as to mix with the vapors therefrom, as indicated in Figure 2. The carburetor and booster device are fed with gasoline from the same fuel tank 3 through a pump 31 operated by motor 32 and run in parallel to the engine manifold 8. The float chamber device has a cylindrical form as shown with its inlet connections 33 at the bottom end portion, and its outlet connection 34 at the top portion adjacent to the connection 35 for the valve 21. The liquid fuel enters the booster device 20 and when filled to a level 36 near the middle causes the ball float 26 to rise, lift its rod 27 and slots 42 and close the inner valve 30 by seating the seat 29 in place. This stops the flow of fuel into this device. When the liquid fuel is drawn or evaporated from the booster chamber, it lowers the ball float 26 causing it to admit more fuel into it through the valve 30, until the chamber is properly filled again to its designated level. The fuel from the booster chamber device passes through the inspirator control device 17 before it reaches the manifold. This inspirator is cylindrical with a piston 37 operating within it, and held under tension in one direction by a coiled spring 38. The walls of the cylinder are provided with an end opening 28 leading to the booster chamber with tubing 19, a side outlet connected with tubing 39 to the manifold 8 and another end opening 40 connected with tubing 18 and adjustment plug 22 to the vacuum connections 41 adjacent the carburetor. It will be noted in Figure 2 that the vacuum created by the moving pistons of the engines (not shown but well understood) acts through the manifold 8, and sucks the gasoline mixture from the float chamber 20 through the tubing 39; while the spark control device 10 has the vacuum created through the outlet 16 spaced away from the first and situated outside of the manifold in the neck of the carburetor. This outlet 16 is disposed at the side entering into an auxiliary chamber and from thence the tubing 41 leads into 14 directly connected with the device 14. The purpose of this auxiliary chamber is to afford a more positive suction on this tubing, than would be provided by the suction on the mouth of the orifice 16.

alone. In action, it is somewhat the reverse to that of a hydraulic ram.

The vacuum operated timing device 10 in this application is of conventional form, but instead of being operated by direct line from the carburetor without modification, as is customary, it is affected by the action, to a modified extent, of the inspirator valve 17. In fact it is actuated in parallel with this valve. This dampens the action of the device, compared with the action of the line 41 thereon without the valve 17 connected to it. Likewise the carburetor has this additional work to do. It operates the inspirator valve 17 to provide an auxiliary supply of fuel to the manifold and also has its supply of fuel to the manifold and also has its supply directed to mix positively with this auxiliary supply. This may be noted in Figure 2. It should be noted that the fuel supply from the pump 31 towards the manifold is bled by the pipe leading to the auxiliary reservoir at 33. This take-off from the carburetor feed modifies the action of the carburetor since it has an interrupting and varied action on the feed to it, as the various other parts of the system operate. These parts include 33, 20, 19, 17, 39 etc. The action is relatively intricate and inherently affects the whole system, which includes the carburetor, manifold, fuel supply and vacuum distributor. The result is a more efficient fuel transmission to the engine and more sensitive reaction to its load requirements.

In the operation of the system, the engine is started and induces a vacuum action on the carburetor and the booster device. Both are induced to deliver their respective mixtures of fuel and air to the manifold where they are mixed and proceed to the engine cylinders for combustion and power. This can be followed along the lines and arrows indicated in Figure 1. The inspirator receives air mixed with fuel vapors in the booster chamber and controls its flow to the manifold. As the engine produces a pulsating vacuum action it releases the piston 37 and partially or fully opens the supply of gas vapors and air mixture from the booster device according to the number of cylinders and speed thereof. At the same time, the carburetor acts likewise. The engine takes the fuel mixture in the conventional manner, but instead of having its carburetor alone, it has the combination mixture from the carburetor and booster device. The mixture being more intimate and without raw particles of fuel to handle provides a more completely and uniformly combined gasoline and air mixture for delivery to the engine cylinder in a form that can be burned more efficiently. The vacuum drawing in the fuel, also controls the position of the distributor sparking, and works on the carburetor and booster device to get the most efficient explosions. It controls the travel of the piston in the inspirator device, and feeds the mixture through it in proportion to the load and engine action. When the engine is stopped and no vacuum action is induced, the spring 38 actuates the piston 37 to close the inlet and outlet of the booster device. When the engine is idling the throttle valve 9 shuts off the vacuum by closing the hole 16 in the carburetor 1. The piston 37 is actuated by the spring 38 and closes off the inlet and outlet of the inspirator 17, cutting off the booster supply.

The action of the gasoline mixtures is dual, in that the engine is fed fuel from two sources, either of which differs in quality from the other. They are mixed together by crossing at right

angles across each others path at a point where each is more or less spread out, and being of different quality, become after mixture, intermediate in quality and close to the explosive mixture sought and desirable. This is because, the carburetor supply discharge is subject to oversaturation, while the booster is subject to undersaturation. Their mixing together resulting in close-to-saturation. The object of passing air through the upper portion of the booster chamber over the vaporizing supply of liquid fuel (like gasoline) settled in the bottom thereof, is to partially enrich the air with same. This is distinct from the operation of the carburetor, which under higher loads particularly, passes the fuel-air mixture saturated with its fuel quota and some of the fuel in drop-like form. The dual supply arrangement using the booster makes the mixture normal and more thoroughly mixed with air. The surrounding of the gasoline with air (or oxygen) gets it ready for more complete combustion, (explosion) than it would if just in the condition that the carburetor alone would inject it. This is particularly the case in the manifold where the space is not restricted, and the two fuel mixtures can expand together as they join.

While but one general form of the invention is shown in the drawings, it is not desired to limit this application to this particular form or in any other way otherwise than limited by the scope thereof, as it is appreciated that other forms could be made that would use the same principles and come within the scope of the appended claims.

Having thus described the invention what is claimed is:

1. In operative combination with the manifold, carburetor, ignition control actuated by suction and fuel connections of an internal combustion engine, an ancillary fuel system comprising in combination, a booster unit for holding an ancillary fuel supply taken from the said connections ahead of the carburetor, float means in the unit for controlling the level of its fuel supply, an air admission valve for combining air with the vapors from the fuel in the said unit, an inspirator having a chamber therein for the reception of fuel, inlet and outlet ports connected with said chamber and the booster unit and the manifold respectively, means in said chamber for opening and closing said ports when actuated by the suction created by the carburetor for operating it and the ignition control for varying the supply of fuel from said inspirator.

2. In operative combination with the manifold, carburetor, ignition control actuated by suction and fuel connections of an internal combustion engine, an ancillary fuel system comprising in combination, a booster unit for holding an ancillary fuel supply taken from the said connections ahead of the carburetor, float means in the unit for controlling the level of its fuel supply, an air admission valve for combining air with the vapors from the fuel in the said unit, an inspirator having a chamber therein for the reception of fuel, inlet and outlet ports connected with said chamber

and the booster unit and the manifold respectively, means in said chamber for opening and closing said ports when actuated by the suction created by the carburetor for operating it and the ignition control for varying the supply of fuel from said inspirator and a reservoir for fuel interposed in the connections between the unit and the fuel supply and having a valve therein for controlling the supply of fuel to the unit therefrom operated by said float.

3. In operative combination with the manifold, carburetor, ignition control actuated by suction and fuel connections of an internal combustion engine, an ancillary fuel system comprising in combination, a booster unit for holding and ancillary fuel supply taken from the said connections ahead of the carburetor, float means in the unit for controlling the level of its fuel supply, an air admission valve for combining air with the vapors from the fuel in the said unit, an inspirator having a chamber therein for the reception of fuel, inlet and outlet ports connected with said chamber and the booster unit and the manifold respectively, means in said chamber for opening and closing said ports when actuated by the suction created by the carburetor for operating it and the ignition control for varying the supply of fuel from said inspirator and a reservoir for fuel interposed in the connections between the unit and the fuel supply and having a valve therein for controlling the supply of fuel to the unit operated by said float, a resilient member for actuating the inspirator in opposition to the suction aforesaid, said system operating together with the said carburetor, manifold, ignition control and fuel connections, so that the increasing of the speed of the engine increases the suction effect thereof on the carburetor and raises the inspirator piston valve to allow a fuller flow of fuel from the booster unit to flow directly into the manifold, while a decrease in speed thereof will cause a reduction in same.
